UNITED STATES PATENT OFFICE.

GUSTAV DE GRAHL, OF ZEHLENDORF, GERMANY.

MECHANICAL STOKER FOR BOILER AND LIKE FURNACES.

1,098,566.

Specification of Letters Patent.

Patented June 2, 1914.

Application filed June 3, 1913. Serial No. 771,450.

To all whom it may concern:

Be it known that I, GUSTAV DE GRAHL, citizen of the German Empire, residing at Zehlendorf, Germany, have invented certain new and useful Improvements in Mechanical Stokers for Boiler and like Furnaces, of which the following is a specification.

This invention relates to an improvement in the form of stoker described in my prior 10 U. S. patent application Serial No. 728,395 filed 29th October 1912, and the object of the present invention is to obtain a more convenient arrangement of rotatable scoop mechanism specially suitable for locomotives.

The invention has also for its object to improve the construction of the stoker and render its operation more effective.

According to this invention the rotatable 20 scoops are mounted to revolve about an axis other than the axle of the locomotive or like wheels. In this way the drum and scoops are not subjected to the shocks received by the axles of the locomotive, and these shocks 25 cannot be transferred through the scoops and drum to the grate bars. It is also of importance to leave the locomotive wheel axles free to be removed for the purposes of repairing or putting new tires on, and the 30 present invention facilitates such dismantling of the locomotive wheel axles.

A further advantage of the present invention resides in the lightness of the parts. The drum itself may be formed of spaced 35 grating bars and all the parts such as the casing and the like may be made considerably lighter owing to the reduction in the amount of shock to which the apparatus is subjected. The invention and the details of 40 construction thereof will be more readily understood from the following description of one convenient form illustrated by way of example in the accompanying drawings in which:—

45 Figure 1 is a side sectional elevation, the section being taken through the fire box of the locomotive and the mechanical stoker. Fig. 2 is an end elevation partly in section. Fig. 3 is an enlarged detail view in side elevation of the drum and the parts of the

casing in the immediate vicinity thereof. Fig. 4 is a view corresponding to Fig. 3, but showing the scoops and clearing members in section. Fig. 5 is a transverse section of the drum on the line A—B of Fig. 4. Fig. 6 55 is detail view showing the method of supporting the curved spaced grating bars which form part of the surface of the drum.

In carrying the invention into effect according to the form illustrated, the locomotive frame A, supports the wheel axles B and 29, in any well known manner. The fire box 1 is arranged to support the grate 2 and ordinary ash box 3 also in the customary manner.

The stoking mechanism, according to the present invention, consists of rotatable scoops carried by a drum 5 which is mounted independently and separately from the wheel axle B and is supported from the locomotive frame A by brackets 20 which engage the shaft 6. The drum 5 is inclosed in a casing C, to which fuel is supplied through suitable openings as hereinafter described, and discharged through other openings at 75 the upper end of the casing. It is clear that in this way the shaft 6 is not subjected to the direct shock to which the axle B is subjected, being cushioned therefrom by the usual springs in the well known manner. 80 The drum 5 is formed as to part of its circumference, of curved grating bars 35 which leave spaces at diametrically opposite points, into which the movable clearing members or rakes are adapted to enter.

The clearing members or rakes 34, are mounted about axes 33 in the neighborhood of the sides of the openings. When the rakes 34 oscillate inward about their axes 33, as shown in the lower part of Fig. 3, the scoops 90 32 are open. At the outermost position of the oscillation of the rakes 34, the scoops are closed.

On the axis 6, cam pieces 40 (see Figs. 3 and 5) are rigidly mounted. Against these 95 cam pieces there bear rollers 38 of interconnected levers 37, the interconnection being provided by the curved yoke piece 45. The purpose of this interconnection is to cause the two rollers 38 to follow the contour of 100

the cam and operate the rakes 34 in unison so that when one rake is in closed position, the other is in open position. The drum 5 is provided at each of its sides, see Fig. 5, 5 with an internally toothed rim 7, the teeth being of ratchet form. Loosely mounted on the axis 6 and at the exterior of the drum, there are two levers 8, one at each side which carry pawls 9 pressed by springs 47 into engagement with the teeth of the ring 7. The lever 8 is caused to oscillate in the manner similar to that described in my prior U. S. application Serial No. 728,395, that is to say through a rod 10 connected to a block 11 in 10 a slotted link 13, pivoted at 12. The link 13 is caused to oscillate by a rod 27, eccentric strap 28, embracing the eccentric 30 mounted on the axle 29. The position of the block 11 in the slotted link 13, may be adjusted 15 by mechanism 18 and 19 as shown. The oscillation of the lever 8 moves the drum 5 around in the direction of the arrow 31 in Fig. 3, the amount of the movement being adjusted by the mechanism described.

25 At one side of the drum there is provided a toothed drum 48, which engages a toothed wheel 50 on a rotatably mounted shaft 49. The shaft 49 also carries a driving wheel 51 connected by a chain to a driving wheel 54 fixed to a rotatable shaft 53. The rotatable shaft 53 carries a rotatable pusher 55 arranged in the chute 4, a short distance to the rear of the stoking device. The pusher 55 is caused to rotate at a speed proportional 20 to that of the drum 5, and push the coal in the chute into the open slots or scoops 32 in the rotatable drum. Beneath the pusher 55, the lower wall is provided with two doors or resilient or yielding panels 60, 61. The panel 60 is rotatably mounted at 62, and the panel 61 is adapted to oscillate about its axis 63. These panels are held in closed position by the springs 64 and 65 respectively (see Figs. 1 and 3). If an excessively large piece of coal or stone, slate or the like enters between the wings 50 and the wall of the chute, the panels 60, 61, may if desired be held in their normally closed position by any suitable means, but I have 35 illustrated springs by way of example only.

Beneath the drum 5, I provide an ash box 56 quite separate from the ash box proper 5 of the locomotive. The box 56 receives any ash or small particles which may pass 40 through the grating of the drum. This ash box is easily accessible and may be readily cleaned out from time to time.

55 I claim:—

60 1. A mechanical stoker for boiler or like furnaces comprising a locomotive frame and axles mounted therein, a stationary furnace grate for the purpose of receiving fuel, a fuel chute and means for raising the fuel from said chute onto the front of the furnace grate, consisting of a shaft secured in

70 said locomotive frame separate from said axles, and a drum formed with one part of its circumference of curved grating bars revolubly mounted on said shaft and provided with a fuel pocket having a movable bottom, means for moving said bottom outwardly from the interior to the periphery of the drum in discharging the fuel upon the grate and for moving said bottom from the periphery to the interior of said drum when receiving fuel from the fuel chute, the upper part of the periphery of said drum being adjacent to the front of said grate, and means for revolving said drum.

75 2. A mechanical stoker for boiler or like furnaces comprising a stationary furnace grate for receiving the fuel, an ash-pit beneath said furnace grate, a fuel chute, and means for raising the fuel from said chute onto the front of the furnace grate consisting of a shaft, a grated drum revolubly mounted on said shaft and provided with a fuel pocket, having a movable bottom, means for moving said bottom outwardly from the interior to the periphery of the 80 drum in discharging the fuel upon the grate and for moving said bottom from the periphery to the interior of the drum when receiving fuel from the fuel chute, the upper part of the periphery of said drum being adjacent to the front of said grate, a box 85 directly beneath said drum and separated from said ash-pit, and means for revolving said drum.

90 3. A mechanical stoker for boiler or like furnaces comprising a stationary furnace grate for receiving the fuel, a fuel chute, and means for raising the fuel from said chute onto the front of the furnace grate, consisting of a shaft, a drum part of which 95 on its circumference being formed of curved grating bars, revolubly mounted on said shaft, and provided with a fuel pocket having a movable bottom, means for moving said bottom outwardly from the interior to the periphery of the drum in discharging the fuel upon the grate and for moving said bottom from the periphery to the interior of the drum when receiving fuel from the fuel chute, the upper part of the periphery of said drum being adjacent to the front of said grate, and means for revolving said drum.

100 4. A mechanical stoker for boiler or like furnaces comprising a stationary furnace 105 grate for receiving the fuel, a fuel chute, a shaft, a drum, formed with part of its circumference of curved grating bars, revolubly mounted on said shaft and provided with a fuel pocket, having a movable bottom, a casing about said drum, means for supplying fuel to said casing, means for moving said bottom outwardly from the interior to the periphery of the drum in discharging the fuel upon the grate and for 110

115 120 125 130

moving said bottom from the periphery to the interior of the drum when receiving fuel from the fuel chute, the upper part of the periphery of said drum being adjacent to the front of said grate, and means for revolving said drum.

In testimony whereof I have signed my

name to this specification in the presence of two subscribing witnesses.

GUSTAV DE GRAHL.
